[57] CLAIM

The ornamental design for a face mask mount for a night vision system, as shown and described.

DESCRIPTION

FIG. 1 is a front view of a face mask mount for a night vision system showing my new design;

FIG. 2 is a left side view thereof;

FIG. 3 is a right side view thereof;

FIG. 4 is a rear view thereof;

FIG. 5 is a top view thereof;

FIG. 6 is a bottom view thereof;

FIG. 7 is a front, bottom and right side perspective view thereof;

FIG. 8 is a rear, top and left side perspective view thereof;

FIG. 9 is a rear, bottom and left side perspective view thereof;

FIG. 10 is a front, top and right side perspective view thereof; and,

FIG. 11 is another front, top and right side perspective view thereof, the broken lines are for purposes of illustration only and form no part of the claimed design.

FIG. 1

FIG. 4

FIG. 5

FIG. 6

FIG. 7

FIG. 8.

Fig. 10.

FIG. 11.
